FIG-3

FIG-2

FIG-1

FIGURE 1 is a front perspective view of a cabinet showing our new design with two of the drawer members in open position;

FIGURE 2 is a side elevational view of one of the drawer fronts thereof; and

FIGURE 3 is a front elevational view of the drawer front of FIGURE 2.

The back of the cabinet and the side not shown are plain and unornamented.

The dominant features of our design reside in the cabinet front disposed of two rows of contiguously aligned drawer members the front portions thereof being substantially triangular in shape and forwardly projecting with respect to the rectangular housing cabinet as shown.

We claim:

The ornamental design for a cabinet, as shown and described.
